COMBINED SOAPING, SCRUBBING, AND SPRAYING DEVICE

William H. Zimbalist, Brooklyn, N. Y.

Application May 1, 1935, Serial No. 19,188

2 Claims. (Cl. 15—129)

My present invention relates to washing and scrubbing devices, and more particularly it pertains to a combined scrubbing, soaping and spraying device for use in washing animals, such as dogs.

One of the primary objects of the invention is to provide a unitary washer device capable of usage, when in assembled state, for soaping and scrubbing; and being further adapted for spraying subsequent to, or prior to, the soaping step by a simple removal of the soap and scrubbing brush.

Another important object of the invention is to provide a multi-function head for a dog washer device, the head being constructed to have a liquid supply chamber, a soap chamber and a scrubbing brush; the liquid supply and soap chambers being separated by a perforated plate which not only acts to feed liquid to the soap chamber, but also functions to support the soap cake; the brush, additionally, acting to positively position the soap cake in its chamber.

Another object of the invention resides in the provision of a readily manipulable washing and scrubbing device for animals wherein a single element is made to simultaneously function as a protective sheath for the flexible water supply pipe feeding water to the washer head; a coupling for positively retaining the outlet of the pipe in operative position at the washer head inlet; and a grip handle for permitting the user to manipulate the washer head with great ease and dexterity.

Still another object of the invention may be stated to reside in the provision of a scrubbing brush for a combined soaping and spraying chamber; the brush being constructed to readily fit upon the exterior surface of the chamber and in contact with a soap cake in the soap section of the chamber.

Still other objects of the invention are to improve generally the construction and efficiency of washing and scrubbing devices for dogs, and more especially to provide a unitary soaping, scrubbing and spraying device which is not only efficient and reliable in actual usage, but is further manufactured and assembled, or disassembled, with facility.

The novel features which I believe to be characteristic of my invention are set forth in particularity in the appended claims, the invention itself, however, as to both its organization and method of operation will best be understood by reference to the following description taken in connection with the drawing in which I have

indicated diagrammatically a construction whereby my invention may be carried into effect.

In the drawing:—

Fig. 1 shows a full size plan view of a device embodying the invention, certain of the brush bristles being omitted to simplify the figure.

Fig. 2 shows a sectional view of the device, the section being taken along line 2—2 of Fig. 1 looking in the direction of the arrows.

Fig. 3 shows a detail front view of the soap chamber and the brush support, a part of the support being broken away.

Fig. 4 is a detail sectional view of the perforated spacer plate prior to assembly in the soap chamber.

Fig. 5 is a magnified view of a detail of the soap chamber and perforated plate when assembled.

Referring now to the accompanying drawing, wherein like reference characters in the different figures designate similar structural elements, it will be observed that the unitary washing and scrubbing device of this invention generally comprises a water supply and soap holder head 1 which is provided with a perforated spacer plate, or disc, 2. The space 2 thus provides a sump, or well, 3 which is fed with water, or other desired liquid, from a supply pipe 4. A soap cake 5 is positioned against the plate 2, and is positively retained in the position shown in Fig. 2 by the inner face of a scrubbing brush 6. The brush 6 is supported by a support ring 7, and the latter is slidable over the external peripheral face of the upper portion of the head 1 when it is desired to assemble the device.

The general elements of the device are assembled in a compact manner, and by having certain of the members perform more than one function it is possible to secure highly efficient spraying, soaping and scrubbing action with a minimum of structural elements. Considering, then, the specific details of the device, and their attendant functions, the head 1 has a substantially circular configuration, and may be fabricated by stamping the member out of a brass blank. The base 1' of the head has rounded edges, and a series of peripheral beads, at substantially the center of the head, divide the latter into lower and upper portions. The upper portion 2' of the head is provided with a slight taper 3' at the rim thereof.

The peripheral beads 8, 9 and 10 (see the magnified view in Fig. 5) are provided in the head 1 by the usual pressing methods; the bead 9 is an external one, whereas spaced, parallel beads 8

and 10 are internal. The bead 8 projects to a greater extent than bead 10 into the interior of the head 1. Each of these beads functions in a different manner; the outer bead 9 functions as 5 a stop, or barrier, for the brush support ring 9, while inner beads 8 and 10 act to positively retain the perforated spacer disc 2 in its median position.

The spacer disc 2 (see the detail in Figs. 4 and 10 5) is stamped from a blank of metal having considerable flexibility and resiliency. The configuration imparted to it is that of a shallow circular dish having a circular wall 11; perforations 11' are provided in the base of the dish. 15 Prior to the assembly of the spacer dish 2 in the head, the dish wall 11 has an outward flare. The angle of flare of the wall 11 is such as to cause the bead 10 to force the wall into the substantially vertical position shown in Fig. 5 when the 20 device is assembled. The height of wall 11 is substantially equal to that of the spacing between the peaks of beads 8 and 10. Thus, when the dish 2 is in the assembled position the lower edge thereof is in tight contact with, and is pressed 25 against, the bead 8. The rim of wall 11 is in contact with the crest of bead 10, and, due to the initial flare of wall 11 and the resiliency of the metal thereof, the dish 2 is rigidly maintained in the position shown.

30 The perforated spacer 2 may be fabricated from a circular blank of any zinc alloy metal, although it is to be understood that any type of metal may be used for this purpose. The blank is provided with perforations prior to the pressing out of the flaring wall; or they may be provided subsequently. The dish 2 is snapped into position (the expression "snap" aptly describes the mode of fixing spacer 2 in position) by placing the inner face of the spacer on a block, and 35 then sharply striking the head downwardly with respect to the spacer.

The spacer 2 divides the interior of the head into the water sump, or supply chamber, 3, and the soap holder section. The liquid flowing into 45 the chamber 3 enters the latter through an inlet tube 12, made of brass, whose inlet opening is flared out over the interior face of the wall 1 as shown in Fig. 1. The flared inlet of tube 12 is soldered in place; thus the inlet to the chamber 50 3 is made watertight. The tube 12 is, further, provided with an external thread 13; a spaced tapered nipple 14 is provided at the inlet end of tube 12.

The flexible liquid feed tube 4, such as rubber 55 tubing, has its feed opening disposed over the tapered nipple 14 as shown. A long rigid handle member 15, made of wood, hard rubber, phenol condensation product or other similar rigid non-metallic material, is provided with a metallic ferrule 16 having an inner thread adapted to cooperate with thread 13. The handle member 15 is 60 provided with a central bore in which is disposed the tubing 4. It will be noted from Fig. 2 that the inner face of the bore grips the feed end of tube 4 because of the action of the tapered nipple 14. Thus, the member 15 performs three simultaneous 65 functions; it acts as a mechanical union for coupling the rubber tube outlet to the nipple 14; it also acts as a protective sheath for the portion 70 of tube 4 adjacent to head 1; finally it serves as a rigid grip device to facilitate manipulation of the washer head.

The tubing 4 may be as long as is desired; it usually terminates with a water supply coupling 75 to facilitate attachment to a water faucet, or

other water supply source (not shown). Of course, it will be clear that a liquid soap supply may be coupled to the feed tube 4. If desired a sufficient amount of liquid soap, as shampoo liquid, may be poured into tube 4 to fill the chamber 3. In such case the rinse water will be allowed to flow into the chamber 3 after the soap has been consumed. 5

Assuming that water is being fed to chamber 3, the water is transmitted through the apertures 11' into the soap chamber which houses the soap cake 5. The latter has a circular shape, and is provided with a central bore 20 which acts as a communicating passage between the perforated plate 2 and the scrubbing brush 6. The soap 15 cake has a diameter whose dimensional relation to the plate 2 and head portion 2' is as shown in Fig. 2. By virtue of the recess in the face of the soap cake adjacent plate 2 the water from most of the perforations 11' is able to contact the 20 soap. Sufficient space is left around the soap cake to permit water to seep into the space and contact with the soap cake surface.

The soap chamber is comprised of two telescoping members. One of these is formed by 25 spacer 2 and the circular wall 2'. The other member, or closure top, is provided by the brush holder ring 7 and the scrubber brush 6 whose configuration is that of an annulus. As shown in Fig. 2 the upper face of the cake 5 projects into 30 the bristles of the brush 6 adjacent it. In this way the cake 5 is snugly maintained between plate 2 and brush 6. The central opening of the brush is in communication with bore 20 and apertures 11'; because of this fact the soapy water is 35 able to reach the bristles of brush 6 and produce suds upon proper manipulation of the brush over the surface to be scrubbed.

The brush itself is formed into an annulus by bending the central interwound wire core 22 40 which supports the bristles. The free ends (not shown) of the support core are intertwined, and the annular shape is thus produced. In Fig. 1 the left half of the bristles of brush 6 are broken away 45 to show the construction of the carrier 22 and the support ring 7. It will be observed that the brush support ring 7 is shaped in circular form and locked into such shape (see Fig. 3) by bending lugs 30, provided on one end 31, over recesses 50 which are provided in the other end.

The brush 6 is maintained in the proper desired position shown in Fig. 2 by means of four spaced, vertical pillars 40. These pillars project from the upper edge of support ring 7 and are integral therewith. Each pillar is somewhat offset from the body of ring 7, and is provided with a pair of parallel, forwardly bent wings, or shoulders 41. The top edge of each pillar is bent in a radial direction so as to provide a retention element 42. Thus, the brush 6 is held in place because the carrier 22 and the bristles in the immediate vicinity are tightly gripped between the elements 42 and the shoulders 41. 60

In use water is allowed to flow into the chamber 3 until it is filled. The faucet feeding tube 4 may then be closed. By gripping handle 15 and scrubbing brush 6 over the hair of the animal to be treated, say a dog, a lather is soon produced. The water flows through apertures 11' into contact with cake 5. The soapy water passes through bore 20 and over the bristles of the brush 6. When it is desired to wash the soap suds from the animal's hair the ring 7 is removed, and the soap cake is taken out of the device. The water is 70 75

turned on at the faucet. The water flowing through apertures 11' produces a fine spray to remove the suds. The dish 2 will remain in its position throughout the operation. The wall 11 is so tightly gripped between beads 8 and 10, that the water pressure will not remove it.

The size of the soap cake can be considerably varied when desired. The central bore 20 may be omitted; and a solid cake with a narrower diameter may be substituted.

While I have indicated and described a system for carrying my invention into effect, it will be apparent to one skilled in the art that my invention is by no means limited to the particular construction shown and described, but that many modifications may be made without departing from the scope of my invention, as set forth in the appended claims.

What I claim is:

1. In a device of the class described, a casing having a base and an open mouth, a perforated plate rigidly fixed within the casing intermediate

the base and open mouth, an orifice in the casing wall between the base and plate, a liquid feed means coupled to said orifice, a circular band in telescopic engagement with the portion of the casing between the plate and mouth, said band being provided with a plurality of spaced brush retainer elements, an annular brush having a carrier core retained in position by said retainer elements.

2. In a device of the class described, a casing having a base and an open mouth, a perforated plate rigidly fixed within the casing intermediate the base and open mouth, an orifice in the casing wall between the base and plate, a liquid feed means coupled to said orifice, a cake of soap positioned on said plate, a brush holder in slidble engagement with the casing adjacent said mouth, and a brush rigidly secured on said holder, said brush and brush holder functioning as a closure for the soap section of the casing.

WILLIAM H. ZIMBALIST.
